(57) **CLAIM**

The ornamental design for a film for making packages, as
 shown and described.

DESCRIPTION

FIG. 1 is a top plan view of a film for making packages; and,
 FIG. 2 is a bottom plan view of the film for making
 packages.

The film has a minimal thickness.

The broken line in the bottom view represents a score line
 on the lower layer of film. The configuration of the score line
 is not part of the claimed design.
